UNITED STATES PATENT OFFICE.

WILLIAM R. FENERTY, OF LOUISVILLE, KENTUCKY.

STOVE-LEG.

SPECIFICATION forming part of Letters Patent No. 240,682, dated April 26, 1881.

Application filed February 25, 1881. (Model.)

To all whom it may concern:

Be it known that I, WILLIAM R. FENERTY, of Louisville, in the county of Jefferson and State of Kentucky, have invented a new and Improved Stove-Leg, of which the following is a full, clear, and exact description.

My invention consists in casting the lower edge of the stove with a downwardly-inclined flange having undercut projections on the inside thereof, in combination with the leg cast with a surrounding shoulder to support the weight of the stove, and with an upwardly-inclined shank the side ends of which are beveled to correspond with the undercut projections, forming a dovetail therewith, the leg being also provided with a central stud for locking the leg to the flange of the stove, as hereinafter fully described.

In the accompanying drawings, Figure 1 is a top view of my invention with a portion of the flange of the stove broken away. Fig. 2 is a front elevation, also with a portion of the flange cut away; and Fig. 3 is a vertical section taken on the line $x-x$ of Fig. 1.

Similar letters of reference indicate corresponding parts.

A represents the leg of the stove, cast with the surrounding shoulder a and with the upwardly-inclined shank b , the side ends, $b' b'$, of which are beveled, as shown. The center of the inclined shank a is cast with the stud d , having the lateral cut or slot d' formed in it.

B represents the edge of the stove-bottom, which is cast with the downwardly-inclined flange e and with the undercut projections e'

e' , and it is also formed with the hole c and provided on the upper side with the pivoted latch or button c' . The edge B is to be secured to the body of the stove by the projections i and by bolts which pass through the holes i' .

Constructed in this manner the leg can always be firmly attached to the stove without much difficulty, and the shank being vertical, the weight of the stove always secures a perfect fit between the edge of the flange and the shoulder, presenting always a good appearance. And, besides, in casting the bottom the undercut projections are solid on the pattern and the castings are always uniform, requiring little or no fitting, thus resulting in great saving of labor.

Instead of using the latch or button c for engaging with the slot in the stud d to fasten the leg to the stove, it is obvious that a nut or key or other means might be employed and not depart from the spirit of my invention.

Having thus described my invention, I claim as new and desire to secure by Letters Patent—

The stove-leg A , formed with the shoulder a and with the upwardly-inclined shank b , and with the stud d , in combination with the inclined flange e , formed with the undercut projection $e' e'$, and having the hole c and locking device c' , substantially as shown and described.

WILLIAM RUFUS FENERTY.
